UNITED STATES PATENT OFFICE.

HERMANN THUN, OF ESSEN-RUHR, GERMANY, ASSIGNOR TO FRIED. KRUPP AKTIEN-GESELLSCHAFT, OF ESSEN-ON-THE-RUHR, GERMANY.

STAMP-DELIVERY MACHINE.

1,382,573.

Specification of Letters Patent. Patented June 21, 1921.

Application filed December 3, 1920. Serial No. 428,089.

To all whom it may concern:

Be it known that I, HERMANN THUN, residing at Essen-Ruhr, Germany, a citizen of the German Republic, have invented a certain new and useful Improvement in Stamp-Delivery Machines, for which I have filed application in Germany May 8, 1919, of which the following is a specification.

The subject matter of the invention is a stamp delivery machine with a counter which shows direct the value of the stamps delivered.

On the drawing an automatic stamp delivery device is shown as an example of construction of the invention, which contains eight kinds of stamps of different value. On this drawing:

Figure 1 is a plan in diagram of the stamp delivery machine.

Fig. 2 is a lateral sectional view of a detail and

Fig. 3 is the front view corresponding to Fig. 2.

On a drum A which can rotate about a vertical shaft B, eight rolls C containing the different strips of stamps are rotatably mounted. The strips of stamps may only be made up of stamps the value of which is divisible by five without remainder. At the side of each roll C an arm D is fixed on the drum A and carries a vertical rod D¹ rigidly connected with it. The rods D¹ are stepped downward to different depths so that stop surfaces d² are formed thereon, which lie at different depths for each individual rod D¹. These depths are determined by the value of the stamp contained in the corresponding stamp roll C and are equal to a unit v, multiplied by the figure which results from division of the value of the various stamps by five (Fig. 2). The rods D¹ are so arranged that their stop faces d² can project into the path of a cam e¹ provided on a vertically slideable rack E guided by two bolts F and F¹.

The rack E can be slid to such an extent that its cam e¹ can come to lie against the deepest stop surface d². Under the action of a tension spring G the rack E lies firmly on the free end of a pivotally mounted single arm lever H, which in turn, owing to the action of a spring (not shown) which is more powerful than the tension spring G, lies against a pin J. The stroke of the lever H is limited downward by a second pin J¹. On a shaft N, mounted in a

cylindrical casing M there is fitted outside the casing M a pinion K, with which the rack E meshes. Inside the casing M the shaft N carries an arm P rigidly fixed thereto, on the free end of which a ratchet R is mounted so as to be able to rotate (Fig. 2) and is under the action of a spring Q. The ratchet R engages in the teeth of a ratchet wheel T which is mounted coaxially with the pinion K in the casing M so as to be resist- 60
ently rotatable, and has twenty teeth t¹. The disposition adopted is such that the ratchet wheel T, when the pinion K rotates clockwise, is made to share in this movement by the ratchet R, but remains station- 65
ary when the pinion K rotates in the opposite direction. The ratio of transmission between the rack E and the pinion K is such as to secure that when the ratchet E de- 70
scends by the amount of the unit v the ratchet wheel T is tripped to the extent of one tooth. On its outer periphery the ratchet wheel T carries the figure 0 and the figures from 5 to 95 divisible, without re- 75
mainder, by 5, these figures being uniformly 80
distributed and visible through a window m¹ provided in the casing M. Adjoining the ratchet wheel T there are mounted so as to be able to rotate loosely on the shaft N, drums provided with figures which are con- 85
nected with each other and with the ratchet wheel T in the known way by Maltese wheels and which show the hundreds, thousands, etc.

If the stamp delivery machine is required to deliver a stamp for instance to the value of 20 pf., the drum A is turned until the rod D¹, corresponding to this value of stamp, is opposite the rack E. If the lever H is now pressed downward till it stops against the pin J¹ then an arrangement, 90
not shown, and connected with the lever H, actuates the stamp delivery device so that the stamp can be taken out. At the same time the spring G draws the rack E downward until the cam e¹ comes to lie against the stop face d². The rack E then, as is 95
evident from what has been said above, descends to 4. v and, through the agency of the pinion K and the ratchet R, effects a trip movement of the ratchet wheel T of 100
four teeth, i. e., an increase of the figures appearing in the window m¹ up to four times five=20, which corresponds to the 105
value of the stamp taken out. After release of the lever H, this lever, under the 110

- action of the spring (not shown), moves upward till it strikes against the pin J and brings back the rack E into its former position against the action of the spring G. 5 The result of this movement is a rotation of the pinion K counter-clockwise. Meanwhile the ratchet R slips over the teeth of the ratchet wheel T, the position of which is therefore not affected by the release of 10 the lever H. When taking out a stamp of the value say of 40 pf., the rack E descends by $8.v$ and causes a trip movement of the ratchet wheel T of eight teeth, therefore an increase of the figure appearing in the window m^1 by eight times five=40, which again corresponds to the value of the stamp taken out. Therefore the counter directly indicates the value of the stamps delivered. 15 If a stamp delivery device is to be designed in accordance with the invention also containing stamps to the value of $2\frac{1}{2}$ and $7\frac{1}{2}$ pfennig, the ratchet wheel must have 100: $2\frac{1}{2}=40$ teeth and the unit v will again be chosen in such a way that when the rack E descends by this unit the ratchet wheel T is tripped on by one tooth. On its periphery the ratchet wheel T carries the figure O and the figures from $2\frac{1}{2}$ to $97\frac{1}{2}$, divisible without remainder by $2\frac{1}{2}$. 20 25 30 Claims. 1. The combination with a stamp delivery machine of a counter, said counter comprising a figure drum provided with figures indicative of the value of stamps delivered, means for rotating said drum, the stamps being carried in rolls, and means adjacent each roll coöperating with said drum operating means for allowing rotation of the drum an amount corresponding to the value 35 40 of the stamp delivered. 2. A stamp delivery machine provided with a plurality of stamp rolls in combination with a counter, said counter comprising a drum provided with figures for indicating the values of the stamps delivered, 45 a rod adjacent each stamp roll, means for operating said drum, said rods coöperating with said drum operating means for limiting the amount of movement imparted thereto, corresponding to the value of the 50 stamps delivered. 3. A stamp delivery machine having a plurality of stamp rolls, in combination with a counter, said counter comprising a drum provided with figures for indicating the 55 value of the stamps delivered, rods mounted adjacent said stamp rolls, shoulders formed on said rods, said shoulders being formed at graduated points from the ends of said rods, a pinion carried by said drum, a rack 60 for operating said pinion, the shoulders on said rods coöperating with said rack to limit the rotation imparted to said drum, corresponding to the value of the stamp delivered. 65 4. A stamp delivery machine having a plurality of stamp rolls in combination with a counter, said counter comprising a figure drum, a pawl and ratchet for rotating said drum, a pinion for operating said pawl, a 70 vertical movable rack meshing with said pinion, a rod positioned adjacent each stamped roll, stops formed on said rods, said stops being positioned on said rods at graduated distances from the ends thereof, a stop on said rack bar, the stops on said rods projecting into the path of the stop on the rack bar to limit the amount of rotation imparted to said drum, as and for the 75 purpose described. 80 The foregoing specification signed at Essen, Germany, this 26th day of July, 1920.
